No. 681,065.

Patented Aug. 20, 1901.

E. E. E. MEARS.

MILL APPLIANCE.

(Application filed May 3, 1901.)

(No Model.)

UNITED STATES PATENT OFFICE.

ELMER E. E. MEARS, OF MUNHALL, PENNSYLVANIA, ASSIGNOR OF ONE-HALF TO GEORGIE M. HOUPP, OF MANSFIELD, OHIO.

MILL APPLIANCE.

SPECIFICATION forming part of Letters Patent No. 681,065, dated August 20, 1901.

Application filed May 3, 1901. Serial No. 58,629. (No model.)

To all whom it may concern:

Be it known that I, ELMER E. E. MEARS, a citizen of the United States, residing at Munhall, Allegheny county, Pennsylvania, have 5 invented certain new and useful Improvements in Mill Appliances, of which the following is a specification, that will enable those skilled in the art to which my invention pertains to make and use the same, reference being had to the accompanying drawings.

My invention relates to mill appliances for handling metallic ingots or slabs, especially for introducing them into and withdrawing them from heating-furnaces. Its objects are 15 to enable the appliance to engage an ingot or slab firmly and securely without the necessity for extreme accuracy as to the points of contact of the jaws of the gripper on the ingot and with a minimum depth of bite of the 20 jaws into the ingot, and therefore small consequent damage to the ingot, and to increase the durability of the jaws; and it consists of such a formation of the jaws of the gripper as will increase their durability and efficiency 25 and enable them to securely grasp an ingot between them and by reason of their long contact-surfaces to hold the ingot from rolling after being grasped by them and on its 30 passage into or from a furnace and to engage it securely without gouging deeply into its surface.

The accompanying drawings show my invention in the forms now considered most desirable by me, but changes in the details and 35 proportions thereof and in the manner of their application might be made without the exercise of invention by a skilful mechanic without departing from the spirit of my invention as set forth in the claims at the end 40 of this specification.

Figure 1 is a perspective view of an ingot-gripping appliance with jaws constructed in accordance with my invention. Fig. 2 is a side elevation of the movable or sliding jaw. Fig. 3 is a plan view of the fixed jaw at the 45 end of the extension-beam or jib. Fig. 4 is a plan view of the same. Fig. 5 is a perspective view of an ingot, illustrating how it may

be engaged to be securely held by a gripper having my improvement. Fig. 6 is a perspective view of the old style of gripper-jaws provided with conical pins or contact-points; and Fig. 7 is a perspective view of an ingot, illustrating how the old style of gripper must engage it to hold it in proper position for 55 passage through a furnace-door.

My present improvement is adapted to mill appliances—such, for instance, as shown in Letters Patent No. 412,851, granted to Kennedy and Aiken October 15, 1889, and No. 60 428,301, granted to S. Forter May 20, 1890, in both of which are shown extension-bars or jibs *a* formed with jaws *b* at their extremities and provided with movable jaw-blocks *c*, mounted upon the bars and adapted to slide 65 therealong toward or away from the fixed jaw at the end of the bar. These bars extend from and are suitably supported by movable carriages or trolleys adapted to move in desired directions and to project the ends 70 of the jibs into the heating-furnaces to deposit or withdraw ingots. The jaws in both these patents and in all the mechanisms of this nature now in general use are armed with conical-pointed spurs or pins, such as 75 are shown at *d* in Fig. 6, and which when the jaws are closed upon the ends of an ingot gouge or dig into its body, making deep pits *e*, as shown in Fig. 7. The doors of ingot-heating furnaces are usually made as 80 small as possible to admit of convenient working through them in order to admit as little cold air as may be while the doors are opened for the passage of ingots, and in most cases the doors are of such dimensions 85 as will barely admit the ingot and the appliance by which it is carried. It is therefore necessary that the ingots should be securely and properly grasped by the gripper and held in fair presentation for the opening 90 through which it must pass. With conical spurs heretofore used the billet if not properly engaged by the spur is liable to roll on them and assume a canting position that would prohibit its passage through a furnace-door. To avoid this, it is necessary to en-

gage the ingot at or near the points shown in Fig. 7—that is, above the center of gravity represented by the horizontal line xx and on or very near the vertical centers represented by the vertical lines yy —so that it will hang suspended on the conical points in proper position. The operator has nothing but judgment and practice to guide him in properly engaging, and with masses of metal more or less irregular, constantly varying in size, and located in highly-heated furnaces the misses come oftener than the correct hits. These misses necessitate the releasing of the ingot to change the application of the gripper-points to new spots, sometimes several changes being necessary before the proper hold is secured. This not only wastes the time of the operator and mechanism, but results in serious loss through the admission of much cold air and the cooling of the furnace. Another objection to the conical points is the slight hold they have on the ingots, particularly on large ingots, which when very hot and soft will by their weight tear away from the points and fall from the grippers, having deep scars in their surfaces, torn through by the points. These scars and even the ordinary deep pits e made by the conical points d are injurious to the ingots, as they form openings, which the subsequent rolling of the ingots will flatten, close, and lengthen, but never weld and heal, so that they form the origin of seams or cracks, which destroy the value of the plates to the full depth to which they extend and cause loss in the cutting off of large portions of the otherwise perfect and sound ends of plates. These three objections—to wit, the difficulty of properly engaging the ingot to hold it in correct position, the tearing away of large heated ingots from the hold of the conical points, and the deep indentations and scars in the ingots caused by these points—are what I seek to overcome by my invention, which consists in forming on each of the jaws of a gripper a long chisel-shaped point or edge f , which lie horizontally and contact with and bite into the ends of the ingots. These edges may be of any suitable length and may be formed integral with the gripper-jaws or made separately and secured thereto in any suitable manner. By reason of their long contacts with an ingot jaws with my improvement grip securely without biting deeply into it. They overcome entirely the danger of the tearing away of large heated ingots and they obviate the necessity for great particularity as to the points of engagement with the ingots to hold them securely against rolling or turning while in the grasp of the gripper. This last point is illustrated by Fig. 5, in which the points of contact gg are shown as being not only below the center of gravity of the ingot, but also slightly to one side of the vertical lines yy , and yet the ingot cannot roll

or turn on the long contacts as it would on 65 conical pins similarly engaged. These long chisel-shaped contacts have a further advantage of not heating and wearing as do the conical points. The latter having small bulk penetrate deeply into the heated ingots and 70 become rapidly heated and worn by the contact, while with my long edges the wearing-surface is greater, the penetration is less, and the greater mass of metal in proximity to the edges tends to keep them cooler by conducting away and absorbing the heat which the edges may acquire in their short periodic contacts with heated ingots. I also slope the inner opposing faces of the jaws up and back from the edges ff , as shown at hh , and find 75 it effective in handling thin ingots or slabs. In such work the edges ff may slip in beneath a thin ingot, and as the jaws close in it will slip up their inclined faces until it contacts with the overlying portion of the beam a , 80 against which it will be securely held against rolling or canting while held by the gripper. 85 In the construction of ingot-heating furnaces heavy iron fronts and door-frames are used, and the floor of the furnace is usually 90 laid on a level with the bottom of the door-opening in the iron front or door-frame. It frequently occurs, either through settling of the masonry or wear, that the floor sinks below the level of the door-opening, leaving the 95 lower edge of the opening in the frame at a distance above the floor. When inserting an ingot into a furnace, the movable jaw c of the gripper seldom passes entirely into the furnace or beyond the door-frame, and if 100 the bottom edge of this jaw is straight, as shown in Fig. 6, it will contact with the raised ledge, which prevents its being lowered to the inner level of the floor. This sometimes compels the opening of the jaws and the release 105 of the ingot while it is suspended away from the floor, to which it drops with results more or less damaging to the furnace. To overcome this objection, I form a curved indentation i in the bottom surface of the jaw, which 110 will permit its point or edge f to drop to the floor-level in depositing an ingot regardless of the differences of level between the bottom of the opening and the floor-surface. This indentation i may be made greater or less 115 than shown in the drawings, as circumstances may require.

Having thus described my invention, what I claim, and desire to secure by Letters Patent, is—

1. The gripper of a mill appliance having adjustable jaws provided with long horizontal contact edges substantially as described.
2. The gripper of a mill appliance having adjustable jaws provided with long horizontal contact edges which are made integral with the jaws substantially as described.
3. The gripper of a mill appliance having

adjustable jaws provided with long horizontal contact edges and having their opposed faces sloping upwardly and outwardly from their respective edges as and for the purpose described.

5. The gripper of a mill appliance having adjustable jaws provided with long horizontal contact edges and opposed, sloping faces, the movable jaw also having a curved in-

dentation in its lower surface substantially 10 as set forth.

In testimony whereof I have signed my name to this specification in the presence of two subscribing witnesses.
